UNITED STATES PATENT OFFICE

166,479

LADY'S STOCKING

Ernest A. Maye, Lenoir, and William M. Powell,
Valdese, N. C., assignors to Lenoir Hosiery Mills,
Inc., a corporation of North Carolina

Application August 30, 1951, Serial No. 16,485

Term of patent 14 years

(Cl. D47--7)

To all whom it may concern:

Be it known that we, Ernest A. Maye and William M. Powell, both citizens of the United States of America, residing at Lenoir, in the county of Caldwell, State of North Carolina and residing at Valdese, in the county of Burke, State of North Carolina, respectively, have invented a new, original, and ornamental Design for a Lady's Stocking, of which the following is a specification, reference being had to the accompanying drawing, forming a part thereof.

We claim:

The ornamental design for a lady's stocking, substantially as shown.

ERNEST A. MAYE.
WILLIAM M. POWELL.
